(57) **CLAIM**

The ornamental design for a combined wireless microphone and vehicle charger adapter, as shown and described.

DESCRIPTION

FIG. 1 is a perspective view of a combined wireless microphone and vehicle charger adapter showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The broken lines in the drawings are for the purpose of illustrating portions of the combined wireless microphone and vehicle charger adapter that form no part of the claimed design.
